UNITED STATES PATENT OFFICE.

JAMES R. NORTHRUP, OF ROCKY BROOK, RHODE ISLAND.

CARRIAGE-SPRING.

SPECIFICATION forming part of Letters Patent No. 376,158, dated January 10, 1882.

Application filed May 6, 1887. Serial No. 237,334. (No model.)

To all whom it may concern:

Be it known that I, JAMES R. NORTHRUP, of Rocky Brook, in the county of Washington and State of Rhode Island, have invented 5 certain new and useful Improvements in Carriage-Springs, of which the following, taken in connection with the accompanying drawings, is a specification.

The object of this invention is to provide a simple, ornamental, and efficient form of carriage-springs in which the vehicle-body is supported by four distinct and independent springs, each extending from one edge of the body transversely across beneath it with a 15 gradual taper, and engaging at its extremity, by a suitable clip, with the side bar. I coil springs entirely around said bars for increased elasticity, and at their inner and thicker ends bend them sharply inward and fix them by a 20 staple securely within a recess in a cross-piece or spring-board on which the carriage-bottom rests.

In the drawings, Figure 1 is a transverse section of the carriage-bottom and side bars, 25 showing the rear axle and spring in elevation. Fig. 2 is a detail in section on the line *x x* of Fig. 1.

A is the axle; B, the rocker-bar resting thereon, and C C the side-bars fixed to the 30 outer ends of the bar B, extending longitudinally to the corresponding part over the front axle.

D is the bottom of the carriage-body, having near each end a sill, bed-piece, cross-piece, or 35 spring-board, E, securely attached thereto. Parts serving as a reach are shown in section at F F, Fig. 1, being simply two rods extending from the rear axle to the front rocker-bar.

G G represent my improved springs, one 40 pair of which is clearly shown in Fig. 1. Each spring is independent of the other and tapers gradually throughout its entire length. The inner and thicker end of each is bent to a U shape, one arm of the U fitting into a longitudinal recess in the bed-piece or spring-board E, and bearing against the under side of the bottom D, while its other arm is prolonged obliquely across to the side bar on the opposite side of the body, and is, by preference, coiled 45 once around said bar. A suitable clip, H,

connects the tip of the spring flexibly or pivotally to the bar.

The short arm of the U at the thick end of the spring, while sunken in a recess in the bed-piece or spring-board E, is secured to said 55 piece by a staple, J, having threaded prongs, passing each side of the spring to the upper surface of the bed-piece or spring-board and furnished with nuts to prevent their withdrawal. When the prongs pass through the 60 solid wood of the bed-piece or spring-board, as in Fig. 2, the nuts with simple washers will ordinarily give abundant support; but when passing each side of said piece, as indicated in Fig. 1, I provide a thin bar or strip of 65 metal, K, through which the prongs pass and on which the nuts bear. This strip is shown in both figures. The body or bottom D is firmly secured to the bed-piece. The thick ends of the springs being held rigidly in the 70 recesses in the bed-pieces, it will be obvious that all the springs co-operate to resist transverse strains upon them caused by any undue longitudinal movement of the body D, and also that downward pressure upon any part of 75 said body is borne by all the springs.

Having described this improvement, I claim—

1. The springs G G, made independent of each other, but arranged in pairs, each fixed 80 firmly at its thickened end beneath one edge of the body D, bent sharply near such edge and extended transversely and obliquely beneath such body with a gradual taper, and connected to the side supporting-bar, substantially as set forth.

2. The carriage-body D, and recessed bed-piece or spring-board E, fixed firmly thereto, in combination with the independent springs G G, mounted in said recesses, and with the securing-staples, substantially as set forth.

In testimony whereof I have signed my name to this specification, in the presence of two subscribing witnesses, on this 5th day of February, A. D. 1887.

JAMES R. NORTHRUP.

Witnesses:

JOHN G. PERRY,
HOWARD B. PERRY.
